(57) **CLAIM**

The ornamental design for a fiber dowel connector, as shown and described.

DESCRIPTION

The patent or application file contains at least one drawing executed in color. Copies of this patent or patent application publication with color drawing(s) will be provided by the Office upon request and payment of the necessary fee.

1.1 is a right side view of the fiber dowel connector;

1.2 is a perspective view thereof;

1.3 is a front view thereof; and

1.4 is a top view thereof.

The blue ribbed bars that are shown rotated through the support with a screw thread form no part of the claimed design. The claimed design is rendered in transparent orange.

1 Claim, 4 Drawing Sheets
